UNITED STATES PATENT OFFICE.

EDWARD WILLIAM MACKENZIE HUGHES, OF CHICAGO, ILLINOIS, ASSIGNOR
TO THE FOX SOLID PRESSED STEEL COMPANY, OF SAME PLACE.

SMOKE-BOX FRONT DOOR..

SPECIFICATION forming part of Letters Patent No. 408,026, dated July 30, 1889.

Application filed January 21, 1889. Serial No. 297,061. (No model.)

To all whom it may concern:

Be it known that I, EDWARD WILLIAM MACKENZIE HUGHES, of Chicago, Cook county, Illinois, have invented a new and useful Improvement in Smoke-Box Front Door and Number-Plate, of which the following is a full, true, and exact description, reference being had to the accompanying drawings.

This invention relates to an improvement in smoke-box front doors and number-plates for locomotives, and is designed to form such front door and number-plate of pressed steel, and having a peculiar corrugation, allowing for expansion and contraction.

15 My invention will be readily understood from the accompanying drawings, in which—

Figure 1 represents an elevation of the front end of the boiler having the front door and number-plate attached thereto, and Fig. 2 is a horizontal section through the same.

20 In my drawings, A represents the exterior circular portion of pressed steel, B the central cover, and C the number-plate. The exterior part of the cover is corrugated, as shown at D, thereby allowing for the expansion and contraction of the metal without liability to fracture.

The central cover B is hinged to the main front and has the general shape shown, and the number-plate C again is fixed 25 to the part B with a distance-piece. These parts are made of sheets of steel pressed to shape between dies by any suitable apparatus—as, for instance, the apparatus shown in the application of Samson Fox, Serial No.

30 261,166, filed January 18, 1888. By making these front end doors and number-plates of pressed steel, instead of cast-iron, it is apparent that such door will be far more durable than cast-iron, owing to the corrugation

35 40 stamped in and around it. Such door is capable of expanding and contracting without cracking, which cast-iron is liable to do, and there will be a great advantage in reduction in weight on the front end of the smoke-box, 45 which is now excessive, owing to the elongated smoke-box carried over the leading truck.

It is likewise exceedingly important to have these front boxes absolutely tight, so as to

prevent the passage of air and consequent 50 combustion of the particles of coal retained therein, and it is practically impossible to keep cast-iron fronts tight. Moreover, a cast-iron front is much more expensive in its attachments, as it requires a large wrought-iron 55 ring tooled on two faces and has to be studded. The steel plate is only riveted to the original sides of the smoke-box. Cast-iron plates split from the variation of temperature in the smoke-box. The steel will not. Cast-iron, 60 owing to its brittle nature and consequent tendency to crack, involves a tedious process in securing the smoke-box door to insure the exclusion of air from the interior of the box. The cast-iron door has to be bolted to the 65 front to obtain this result. The steel door being pliant makes a perfect air-tight joint when the same is drawn up. Every effort is now being made to reduce the weight of the front end of the locomotive. A cast-iron 70 front and attachment weighs eleven hundred and fifty-eight pounds. The steel front weighs two hundred and fifty-three pounds—a saving of nine hundred and five pounds of useless dead load.

Owing to the great lightness obtainable by the use of steel fronts and doors, the danger of hot boxes and broken axles in engine-trucks and leading-wheels will be diminished to a minimum.

75 What I claim as my invention, and desire to secure by Letters Patent, is—

The combination of a flexible corrugated front plate for locomotives, made of pressed steel pressed between dies, of a flexible door 85 itself made of pressed steel pressed between dies and having an elastic action in connection with said front plate, thereby enabling a tight joint to be made between the door and the front plate, substantially as described.

80 In testimony whereof I have signed my name to this specification in the presence of two subscribing witnesses.

EDWARD WILLIAM MACKENZIE HUGHES.
